SEWING MACHINE WORK GUIDE

Nicholaus Knaus, Cranford, and Agnes G. Millington, Clifton, N. J., assignors to The Singer Manufacturing Company, Elizabeth, N. J., a corporation of New Jersey

Application November 9, 1950, Serial No. 194,756

9 Claims. (Cl. 112—136)

1

This invention relates to improvements in work-guides for use in connection with sewing machines and has for its primary object to facilitate the attachment of one or more cords to an elongated tape of the type employed in separable fasteners. More specifically, the invention relates to an improved attachment comprising means for guiding a tape and a pair of cords to the stitch-forming mechanism of a sewing machine in a manner such that one cord will be disposed above and the other cord below the tape with both cords at one edge portion of the tape, whereby both cords will be stitched to the tape in one line of stitching.

With the above and other objects in view, as will hereinafter appear, the invention comprises the devices, combinations, and arrangements of parts hereinafter described in connection with the accompanying drawings, which illustrate a preferred embodiment of the invention and in which:

Fig. 1 represents a top plan view of a sewing machine in which the present invention is incorporated.

Fig. 2 represents, on an enlarged scale, a fragmentary top plan view of the stitching area of the sewing machine disclosed in Fig. 1.

Fig. 3 represents, on an enlarged scale, a sectional view taken substantially along the line 3—3 of Fig. 1.

Fig. 4 represents, on an enlarged scale, a sectional view taken substantially along the line 4—4 of Fig. 1.

Fig. 5 represents a sectional view taken substantially along the line 5—5 of Fig. 2.

Fig. 6 represents a top plan view of the stitching area of the present sewing machine, with the presser-bar swung to its inoperative position and with a portion of the attachment removed from the machine so as better to illustrate the presser-foot.

Fig. 7 represents a fragmentary right-side view of the attachment as disclosed in Fig. 6.

Fig. 8 represents, on an enlarged scale, a top plan view of the sewing machine throat-plate, the feed-dog and the lower cord-guide.

Fig. 9 represents, on an enlarged scale, a bottom plan view of the presser-foot employed in the present attachment.

Fig. 10 represents a sectional view taken substantially along the line 10—10 of Fig. 2.

Fig. 11 represents, on an enlarged scale, a sectional view taken substantially along the line 11—11 of Fig. 1.

Referring more specifically to the drawings, the invention is disclosed as embodied in an overedge sewing machine of the type disclosed in United

2

States patent of N. Knaus, No. 2,238,796, April 16, 1941.

The present machine has a main frame 15 which carries a horizontally disposed work-support 16 through which operates a serrated feed-dog forming a part of a work-feeding mechanism hereinafter referred to. The main frame also supports an overedge stitch-forming mechanism comprising a reciprocating curved needle 17, an under or needle-loop taking looper 18, and an overedge looper or loop-spreader 19 which cooperates with the needle 17 and looper 18 in the formation of overedge stitches. The machine also includes a conventional work-feeding mechanism, designated generally by the numeral 20, and a cooperating presser device for advancing the work to and beyond the stitch-forming mechanism. The presser device comprises a horizontally disposed spring-depressed presser-bar 21 pivoted at its rear end to the machine frame and carrying, at its forward end, a presser-foot 22 which overlies the serrated feed-dogs 23 which form a part of the work-feeding mechanism 20.

As hereinabove indicated, this invention relates primarily to improved means embodied in a machine of the type described for presenting a tape and a pair of cords toward the stitch-forming mechanism in a manner such that one cord is disposed above and the other cord below the tape and with both cords at one edge portion of the tape whereby both cords will be stitched to the tape in one line of stitches. In this connection, reference may be had to Fig. 11 which represents a section through a completed portion of the work. In this figure, the tape is represented by the numeral 24, while the numerals 25 and 26 represent, respectively, the upper and lower cords which are secured to the tape by a conventional overseaming stitch which includes a needle thread 27 and a looper thread 28.

The present attachment includes a throat-plate 29 which is adjustably secured to the work-supporting means 16 by a pair of screws 30, 30, of which each passes through an enlarged aperture 31 to be threaded within apertures 32 provided in the work-supporting means 16. Thus, the throat-plate 29 may be adjusted back and forth laterally of the direction of work feed. This throat-plate 29 is provided in a conventional manner with a plurality of slots 33, 33, of which each is adapted to receive a respective one of the feed-dog elements 23, 23. It is to be particularly noted that the throat-plate 29 is provided rearwardly of the point of seam formation with a pair 55 of aligned grooves 34, 34 which are in turn aligned

with a pair of grooves 35, 35 disposed within a pair of the feed-dog elements 23, 23 spaced from each other in the line of seam formation. These grooves 34 and 35 are adapted to assist in directing the lower cord 26 to and past the stitching means in a manner which will be hereinafter described.

Referring particularly to Figs. 5, 7 and 8, the right-hand edge portion of the throat-plate 29 is provided with an arm 36 which is pivotally secured to the right-hand edge of the throat-plate by means of a pivot screw 37. The forward portion of the arm 36 is provided with a head member 38 formed with a lower-cord receiving groove 39 which is of the so-called self-threading type due to the fact that it communicates with an upwardly open relatively narrow slot 39'. A cord 26 may be positioned within the groove 39 by threading the same through the slot 39' and it is to be particularly observed that the groove 39 is aligned with the grooves 34 and 35 provided, respectively, in the throat-plate 29 and the feed-dog elements 23. When the lower cord groove 39 is in its operative position, as illustrated in Figs. 2 and 8, the head portion 38 of the arm 36 rests upon a shelf portion 40 formed in the throat-plate 29. However, when it is desired to thread the lower cord through the groove 39, the presser-foot 22 may be swung to one side and the screw 37 may be loosened so as to permit the arm 36 to be elevated in a manner as illustrated in Fig. 7, in which position the operator may readily thread the lower cord through the slot 39' and into the groove 39. Thereafter the arm 36 may be swung to its horizontal position and the screw 37 tightened so as to lock the arm in its operative position.

Referring particularly to Figs. 2, 5, 6 and 9, there is provided a presser-foot 22 which is adapted to cooperate with the feed-dog elements 23, 23 in the feeding of work to and past the stitching mechanism. This presser-foot includes an elongated sole-plate 41 having upper and lower surfaces 42 and 43 as well as an upturned toe portion 44. The upper surface 42 of the sole-plate is provided with a transverse arcuate groove 45 which receives therein an arcuately formed pivot member 46 carried upon the lower or forward end of the presser-bar 21. An arm 47, secured to the upper surface of the sole-plate by means of a screw 48, overlies the member 46 so as to hold the member 46 and the throat-plate in a pivotal relation. Thus, the presser-bar 21 normally functions to bias the presser-foot downwardly toward the feed-dogs and the arm 46, along with the plate 47, permits the presser-foot to pivot about the arm 46 in a conventional manner. Fig. 6 illustrates the presser-foot 22 in its operative position but with its presser-bar 21 swung in a horizontal plane to an inoperative position so as better to illustrate the component elements of the presser-foot.

Referring particularly to Figs. 2, 6, 9, and 10, the upper portion of the presser-foot 22 is provided with a transverse slot 49 which slidably receives a block or base member 50. As may be best seen from Fig. 10, the block 50 is provided with an enlarged aperture 51 which is adapted to receive the above noted screw 48 which functions to lock the block in any one of a plurality of selective positions of adjustment relative to and laterally of the presser-foot. As is disclosed in Figs. 2, 3, 6 and 9, the right-hand end portion of the block 50 carries an elongated member 52 which is provided with a downwardly in-

clined cord-guiding groove 53 which communicates with the outside by means of a constricted self-threading slot 54. It is the function of the groove 53 to receive the upper cord 25 and to guide the same directly in the line of needle reciprocation and beneath the tail portion of the presser-foot 22. In this connection, reference may be had to Fig. 2 which illustrates the upper cord 25 as being directed through the groove 53 and in the path of the needle 17 so that the latter will penetrate the cord. Due to the fact that the block 50 is slidably mounted within the presser-foot 22, it is manifest that the upper thread-guiding groove 53 may be adjusted transversely of the direction of feed so that the cord 25 will always be presented directly in the path of the needle 17.

Referring particularly to Fig. 9, it is to be noted that the trailing end portion of the presser sole-plate 43 is provided with an elongated groove 56 which is aligned with the thread-guiding groove 53 so as to receive the lower cord 26 as the same passes beyond the stitching point. As may be best observed from Figs. 2, 3, 5 and 6, the upper forward portion of the presser-foot is provided with a stationary eyelet 57 which is adapted to guide the upper cord 25 to the cord groove 53. Referring to Fig. 3, the lower portion of the arm 52 is provided with a depending finger element 58 which normally projects below the lower surface 43 of the sole-plate so as to guide the right-hand edge of the tape 24 in a manner as will be hereinafter described in more detail.

The trailing portion of the arm 52 is bifurcated in a manner as is best disclosed in Figs. 2 and 9, thereby to form a needle-receiving passage 59 which intersects the longitudinal axis of the thread-guiding groove 53. From this, it is manifest that as the needle 17 reciprocates back and forth, it will, of necessity, have to pass directly through the upper cord 25 which is positively directed into the needle path by means of the bifurcated portion of the arm 52. Referring particularly to Figs. 2 and 3, it is also manifest that the bifurcated portion of the cord-guiding arm 52 is disposed directly beneath the path of movement of the looper element 19 so that, in the normal operation of the sewing machine, the thread loops will be concatenated about the bifurcated portion of the arm in a manner such that this arm will function as a conventional chaining-off finger. Thus the arm 52 serves a two-fold purpose, to wit: it functions as a cord-guide which positively directs the upper cord 25 into the path of the needle and, at the same time, it functions as a conventional chaining-off finger to facilitate the production of overedge stitches about the edge of the work.

In order to facilitate the lateral adjustment of the base member 50 of the upper cord-guiding member 52, the present attachment is provided with a micrometer adjusting screw 60 which is threaded directly within the forward portion of the presser-foot 22. This screw 60 is formed with a cylindrical shoulder element 61 which is disposed within a slot 62 provided in the block 50. From this, those skilled in the art will readily appreciate that as the screw 60 is turned so as to shift the same inwardly toward or outwardly from the presser-foot, it, at the same time, functions to shift the block 50 laterally of the presser-foot, thereby to adjust the cord-guiding arm 52 relative to the path of needle reciprocation. Once the cord-guiding arm has been properly positioned by means of the micrometer screw 60,

the block 50 may be effectively locked in such position by means of the screw 48.

For guiding a tape 24 to the stitching mechanism, the present attachment includes an arm 63 which is pivotally mounted upon the main frame 15 of the machine by means of a vertically disposed pivot screw 64. This arm 63 may be swung away from its operative position, disclosed in Fig. 1, to give access to the stitching mechanism. The forward portion of the arm 63 is provided with a depending pin 65 (see Fig. 4) which engages the forward portion of the work-supporting means 16 to locate the arm in its operative position. As is best disclosed in Figs. 1, 3 and 5, the free end portion of the arm 63 is provided with a tape-guiding and -tensioning means, the details of which do not form a part of the present invention and thus will not be described herein. It is sufficient to state that the tape-guiding means comprises a head member 66 which is provided with a laterally elongated tape-receiving slot 67 which functions to direct a tape directly toward the stitch-forming mechanism. Also, the head 66 is provided with a pair of guiding elements 68 and 69 which engage the edge portions of the tape so as to prevent the same from shifting laterally of the presser-foot. It will be particularly observed from Figs. 1 and 4 that the guide members 68 and 69 are laterally adjustable relative to the head 66 by means of adjusting screws 70 and 71, which screws are mounted in the member 66 and pass through enlarged apertures 72, 72 formed in the members 68 and 69. By adjusting the elements 68 and 69 laterally of the presser-foot, the tape may be properly directed toward the stitching mechanism in a manner such that the right-hand edge portion of the tape will be properly aligned relative to the upper and lower cords 25 and 26. A conventional tension device 73 is provided upon the head 66 for applying a tension upon the tape 24.

Referring particularly to Fig. 1, the sewing machine is disclosed as being supported upon a horizontally disposed table 74, of which the forward portion extends about the left-hand portion of the machine so as to provide a small platform member 75. Projecting upwardly from the platform member 75 is a bracket 76, of which one portion carries a conventional tensioning device 77 for receiving a pair of cords 25 and 26 and for tensioning them and directing them toward the stitching mechanism. Also projecting upwardly from the bracket 76 is a pin 78 about which the tape 24 may be trained preparatory to directing the same to the tensioning and guiding head 66.

From the above, it is to be understood that the tape 24 may be led about the upstanding pin 78 and thereafter directed to and through the tensioning and guiding means 66, after which the tape is directed beneath the presser-foot and above the throat-plate in a conventional manner. As hereinabove noted, the right-hand edge portion of the tape 24 is properly guided toward the stitching mechanism by means of a depending finger 58 carried on the upper cord-guiding arm 52.

The upper cord 25 is directed from a source of supply through the tensioning means 77 and thereafter through the eyelet 57 carried upon the forward portion of the presser-foot after which it is directed to the passageway 53 of the guiding arm 52, which passageway functions as above described to direct the cord within the path of the needle 17 so that the latter will puncture the

cord. The lower cord 26, like the upper cord, is directed through the primary tensioning means 77 and thereafter it passes through a slot 79 formed in the arm 63 after which it passes directly beneath the tape 24 and the presser-foot 22 so as to lie within the groove 35 of the forward feed-dog element 23. Thereafter, the lower cord passes directly through the groove 39 in the arm 36, which groove directs the cord into the path of the needle 17, after which the cord lies within the aligned grooves 34 and 35 of the throat-plate and the rearward feed-dog element 23. Since the throat-plate 29 is adjustable laterally of the presser-foot, the lower cord receiving-groove 39 may be shifted so that its longitudinal axis will intercept the path of needle reciprocation to the end that the needle will penetrate the lower cord after the needle passes through the upper cord 25 and the tape 24. Furthermore, as hereinabove noted, the upper cord-guiding groove 53 may be shifted laterally of the presser-foot by means of the micrometer screw 60 so that the upper cord 25 will be properly pierced by the needle 17. Thus, the present attachment provides means for guiding a tape 24 and a pair of upper and lower cords 25 and 26 toward the stitch-forming mechanism, with the one cord 25 disposed above and the other cord 26 disposed below the tape 24 and with both cords at one edge portion of the tape whereby both cords will be stitched to the tape in a single line of stitching. Furthermore, the present attachment provides upper and lower cord-guiding elements 52 and 38 which are individually adjustable laterally of the presser-foot so as properly to position the cord within the path of the reciprocating needle.

In order to prevent the presser-foot 22 from shifting laterally of the direction of feed and thereby shifting the upper cord guide out of its proper position, the present attachment is provided with means for guiding the presser-foot into a fixed lateral position at all times during the operation of the machine. Referring particularly to Figs. 2 and 5, the present attachment includes a platform member 80, of which the forward portion is secured directly to the throat-plate 29 by means of a pair of screws 81, 81. Each of these screws 81 is threaded directly within a suitable aperture 82 provided in the throat-plate 29 and passes through a suitable slot 83 formed in the platform 80 so as to permit the latter to be adjusted laterally of the throat-plate 29. This platform 80 is provided with a pair of parallel grooves 84 and 85 which are disposed crosswise of the direction of work feed and each of which receives therein one of a pair of guide arms 86 and 87. Each of these guide arms 86 and 87 is provided with a suitable slot 88 which is adapted to receive therein the shank portion of a screw 89 which is threaded directly within the platform member 80 in a manner such that its associated guide element 86 or 87 may be adjusted longitudinally of its slot. Referring particularly to Fig. 2, it will be observed that the right-hand end portion of the guide 86 is adapted to abut directly against the forward or toe portion 44 of the presser-foot, while the rearward guide 87 is adapted to abut directly against the left-hand marginal edge of the tail portion of the presser-foot, thereby accurately to position the presser-foot so that it cannot move in a left-hand direction. Cooperating with the guide elements 86 and 87 is a third guide element 90 which is secured directly to the throat-plate 29 by means of a lock-screw 91 which is threaded directly with-

in an aperture 92 provided in the throat-plate 29 in a manner as is best disclosed in Figs. 2 and 3. The screw 91 passes through an enlarged aperture 93 provided in the block 90 so as to permit the block to be shifted laterally of the direction of feed so that the block may cooperate with the elements 86 and 87 in locking the presser-foot in a fixed lateral position. In other words, the guide elements 86 and 87 each engages the left-hand edge while the guide 90 engages the right-hand edge of the presser-foot thereby to determine a fixed position for the presser-foot so that the latter cannot move laterally and thereby disturb the proper relationship between the upper cord guide 52 and the reciprocating needle 17. By means of their locking and positioning screws, each of the guide elements 86, 87 and 90 may be shifted laterally of the direction of feed so as to alter the position of the presser-foot to suit the needs of any one particular job. It should be understood, however, that the guides 86, 87 and 90 do not in any way interfere with the vertical movements of the presser-foot, which movements are produced by the usual feeding action.

The tape 24, with its upper and lower cords 25 and 26 secured to the right-hand edge portion thereof by means of overedge stitches, is fed away from the stitching mechanism by means of the feed mechanism 20 and the presser-foot 22, and in order to insure that the finished tape will be properly delivered away from the sewing machine the table 74 may be provided, if desired, with a special tape-pulling mechanism which is generally designated by the numeral 95. This tape-pulling mechanism forms no part of the present invention and thus it is sufficient to state that it is provided with a pair of feed rollers of which only the upper roller 96 is illustrated in Fig. 1. These feed rollers are adapted to be rotated in opposite directions so as to pull the tape away from the stitching area. The upper and lower feed rollers may be driven in a conventional manner by suitable mechanism actuated by a belt 97 which may be trained over a conventional balance wheel pulley 98 provided upon the sewing machine proper.

Having thus set forth the nature of the invention, what we claim herein is:

1. In a sewing machine for producing a beaded edge tape for separable fastener stringers and having stitch-forming and work-feeding means, work-supporting means, and a presser-foot disposed above said work-supporting means and cooperating with the work-feeding means; the combination therewith of means for directing tape beneath the presser-foot and toward the stitch-forming means, and a pair of guides for guiding a pair of cords toward the stitch-forming mechanism with one cord disposed above and the other cord below the tape and with both cords at one edge portion of the tape whereby both cords will be stitched to the tape in one line of stitching, one of said guides being carried upon and mounted for adjustment laterally of the presser-foot, while the other guide is adjustably carried upon the work-supporting means at a location directly beneath the other guide for movement laterally of the presser-foot.

2. In a sewing machine for producing a beaded edge tape for separable fastener stringers and having stitch-forming and work-feeding means, work-supporting means, and a presser-foot disposed above said work-supporting means and cooperating with the work-feeding means; the combination therewith of a throat-plate mounted

upon the work-supporting means and beneath the presser-foot for adjustment laterally of the presser-foot, means for directing a tape between the presser-foot and said throat-plate and toward the stitch-forming means, and a pair of guides for directing a pair of cords toward the stitch-forming mechanism with one cord disposed above and the other cord below the tape and with both cords at one edge portion of the tape whereby both cords will be stitched to the tape in one line of stitching, one of said guides being carried upon and mounted for adjustment laterally of the presser-foot, while the other guide is carried directly upon said throat-plate at a location directly beneath the other guide so as to be adjustable therewith laterally of the presser-foot.

3. In a sewing machine for producing a beaded edge tape for separable fastener stringers and having stitch-forming and work-feeding means, work-supporting means, and a presser-foot disposed above said work-supporting means and cooperating with the work-feeding means; the combination therewith of a throat-plate mounted upon the work-supporting means and beneath the presser-foot for adjustment laterally of the presser-foot, means for directing a tape between the presser-foot and said throat-plate and toward the stitch-forming means, a pair of guides for directing a pair of cords toward the stitch-forming mechanism with one cord disposed above and the other cord below the tape and with both cords at one edge portion of the tape whereby both cords will be stitched to the tape in one line of stitching, one of said guides being carried upon and mounted for adjustment laterally of the presser-foot, while the other guide is carried directly upon said throat-plate at a location directly beneath the other guide so as to be adjustable therewith laterally of the presser-foot and an abutment element carried upon said throat-plate for engagement with a side portion of the presser-foot thereby to maintain the latter in a proper lateral relation with respect to the stitch-forming mechanism.

4. In a sewing machine for producing a beaded edge tape for separable fastener stringers and having stitch-forming and work-feeding means, a work-supporting throat-plate, and a presser-foot disposed above said throat-plate and cooperating with the work-feeding means; the combination therewith of means for directing a tape between the presser-foot and the throat-plate and toward the stitch-forming means, a pair of guides for guiding a pair of cords toward the stitch-forming mechanism with one cord disposed above and the other cord below the tape and with both cords at one edge portion of the tape whereby both cords will be stitched to the tape in one line of stitching, one of said guides being carried upon and mounted for adjustment laterally of the presser-foot while the other guide is carried directly upon the throat-plate and directly beneath the other guide, and an abutment element and a secondary tape-guiding element each mounted directly upon and for lateral adjustment relative to the throat-plate, said two elements being adapted for engagement respectively with a side portion of the presser-foot and an edge portion of the tape thereby to maintain the presser-foot and the tape in proper lateral relation with respect to the stitch-forming mechanism.

5. In a sewing machine for producing a beaded edge tape for separable fastener stringers and

having stitch-forming means including a reciprocable needle, work-feeding means, work-supporting means, and a presser-foot disposed above said work-supporting means and cooperating with the work-feeding means; the combination therewith of means for directing a tape beneath the presser-foot and toward the stitch-forming means, a pair of guides for directing a pair of cords toward the stitch-forming mechanism with one cord disposed above and the other cord below the tape and with both cords at one edge portion of the tape whereby both cords will be stitched to the tape in one line of stitching, a first one of said guides being carried upon the presser-foot so as to be adjustable laterally thereof, the free end portion of said first guide being bifurcated to define a passage for the needle, and the other of said guides being mounted upon the work-supporting means directly beneath the other guide for lateral adjustment relative to said latter means.

6. In a sewing machine for producing a beaded edge tape for separable fastener stringers and having stitch-forming means including a reciprocable needle and an overedge looper, work-feeding means, work-supporting means, and a presser-foot located above said work-supporting means and cooperating with the work-feeding means; the combination therewith of means for directing a tape beneath the presser-foot and toward the stitch-forming means, and a pair of guides for directing a pair of cords toward the stitch-forming mechanism with one cord disposed above and the other cord below the tape and with both cords at one edge portion of the tape whereby both cords will be stitched to the tape in one line of stitching, a first one of said guides being carried upon the presser-foot and being formed substantially as an elongated tube having a bifurcated free end portion which is disposed within the path of needle reciprocation and beneath the path of movement of the overedge looper so as to define a passage for the needle and to function as a chaining-off finger, while the other guide is carried upon the work-supporting means at a location directly beneath the other guide.

7. In a sewing machine for producing a beaded edge tape for separable fastener stringers and having stitch-forming means including a reciprocable needle and a overedge looper, work-feeding means, work-supporting means, and a presser-foot disposed above said work-supporting means and cooperating with the work-feeding means; the combination therewith of means for directing a tape beneath the presser-foot and toward the stitch-forming means, a pair of guides for directing a pair of cords toward the stitch-forming mechanism with one cord disposed above and the other cord below the tape and with both cords at one edge portion of the tape whereby both cords will be stitched to the tape in one line of stitching, a first one of said guides being carried upon and mounted for lateral adjustment relative to the presser-foot and being formed substantially as an elongated tube having a bifurcated free end portion which is disposed within the path of needle reciprocation and beneath the path of movement of the overedge looper so as to define a passage for the needle and to function as a chaining-off finger, while the other guide

is carried upon and mounted for lateral adjustment relative to the work-supporting means at a location directly beneath the other guide, and a finger depending from said first guide for engaging an edge portion of the tape thereby to position the tape relative to the stitching mechanism.

8. In a sewing machine for producing a beaded edge tape for separable fastener stringers and having stitch-forming means including a reciprocable needle and an overedge looper, work-feeding means, work-supporting means, and a presser-foot disposed above said work-supporting means and cooperating with the work-feeding means; the combination therewith of a throat-plate mounted upon the work-supporting means for adjustment laterally of the presser-foot, means for directing a tape between the presser-foot and said throat-plate, a pair of guides for directing a pair of cords toward the stitch-forming mechanism with one cord disposed above and the other cord below the tape and with both cords at one edge portion of the tape whereby both cords will be stitched to the tape in one line of stitching, a first one of said guides being carried upon the presser-foot and being formed substantially as an elongated tube having a bifurcated free end portion which is disposed within the path of needle reciprocation and beneath the path of movement of the overedge looper so as to define a passage for the needle and to function as a chaining-off finger, while the other guide is carried upon said throat-plate at a location beneath the other guide, and an abutment

35 element and a secondary tape-guiding element each mounted directly upon and for lateral adjustment relative to said throat-plate, said two elements being adapted for engagement respectively with a side portion of the presser-foot and an edge portion of the tape thereby to maintain the presser-foot and the tape in proper lateral relation with respect to the stitch-forming mechanism.

9. A sewing machine attachment including a presser-foot having an elongated sole portion with upper and under surfaces, and a cord-guiding element carried by said sole portion; said cord-guiding element including a base member secured upon the upper surface of said sole portion, and an elongated cord-guiding tube carried upon said base member adjacent one side of said presser-foot with the entrance and delivery ends of said tube disposed respectively at the upper and under surfaces of said presser-foot, the delivery end of said tube having a bifurcation providing a needle-receiving passage intersecting the longitudinal axis of said tube and having its center lying in a plane disposed at right angles to the upper surface of said presser-foot.
